[57] CLAIM

The ornamental design for a vehicle distress beacon, as shown and described.

DESCRIPTION

FIG. 1 is a front elevational view of the vehicle distress beacon of the present invention, with the cord broken away to indicate indeterminate length;

FIG. 2 is a back elevational view of the vehicle distress beacon of FIG. 1;

FIG. 3 is a left side elevational view of the vehicle distress beacon of FIG. 1;

FIG. 4 is a right side elevational view of the vehicle distress beacon of FIG. 1;

FIG. 5 is a top plan view of the vehicle distress beacon of FIG. 1; and,

FIG. 6 is a bottom plan view of the vehicle distress beacon of FIG. 1.
